UNITED STATES PATENT OFFICE.

JOHN M. GALE, OF EATON, OHIO.

SAFETY CASH CABINET.

Application filed November 3, 1922. Serial No. 598,901.

To all whom it may concern:

Be it known that I, JOHN M. GALE, a citizen of the United States, residing at Eaton, in the county of Preble and State of Ohio, have invented certain new and useful Improvements in Safety Cash Cabinets, of which the following is a specification, reference being had therein to the accompanying drawings.

10 My invention relates to safety cash cabinets.

It is the object of my invention to provide means of locking a drawer, particularly a cash drawer, in such a way as to indicate 15 whether the drawer has been tampered with by an unauthorized person.

It is a further object of my invention to provide a drawer which is particularly adaptable for use in banks and other places 20 where valuables are kept in drawers and where a plurality of persons either have access to the drawer or may be in its vicinity and it is desired to close the drawer and prevent its being opened without that fact being indicated.

It is a further object of my invention to provide an autographic means of indicating who effected the closing of the drawer and put it in this locked position.

30 It is an additional object to provide means for rendering such locking mechanism inoperative when desired, and means of maintaining the several parts in operative relationship with one another.

35 It will be understood that in country banks where the cage system is not in vogue, it is essential that some system be devised for permitting the cash drawer of a particular clerk to be closed and kept closed during the 40 clerk's absence to prevent tampering with that particular drawer by unauthorized persons.

Referring to the drawings:

Figure 1 is a perspective of the top of a cabinet with a drawer partially open.

Fig. 2 is a detail of the mechanism carried by the drawer and the guide carried by the wall of the cabinet.

Fig. 3 is a section through the mechanism.

50 Fig. 4 is a detail of the mechanism partially in section.

Fig. 5 is a perspective of one of the autographic cards;

Fig. 6 is a side elevation of the mecha-

nism with the drawer closed, the outer wall 55 being removed to disclose the mechanism.

In Fig. 6 the autographic card is in place; Fig. 7 is a similar view with the drawer just about to be closed;

Fig. 8 is a similar view with the drawer 60 open.

Referring to the drawings in detail:

1 is a side wall of the cabinet having corner posts 2.

3 is a front wall of this cabinet and 4 is 65 the top. A cabinet is provided with a drawer 5 which is equipped with side walls 6. A notch 7 is cut in the face 3 to permit of the passage of a knife support bracket 8 which is carried by the drawer side wall 6. 70 This drawer side wall also supports the elevator member 9 which is fastened to the side wall 6 by the pins 10 and 11 in a stationary inclined position. The upper and forward end of 9 is provided with a notch 12 for 75 the reception of a guiding and elevating pin 13 which is carried by a knife plunger 14. A swinging pin guard 15 is pivoted at 16 to the side wall 6 directly above the knife support 8. A vertical guiding member for the knife 80 plunger is carried by the side wall 6 and designated 17.

The lower end of the elevator consists of a freely moving part 18 having a tapered nose or cam surface 19. 18 is pivoted to the 85 elevator proper 9 which is stationary as at 20. This movable portion of the elevator is limited in its upward movement by the stop pin 21 and in its lower movement by the stop pin 22, both of the pins being carried 90 by the side wall 6 of the drawer. When it is desired to render the mechanism inoperative 18 can be held in elevated position by a swinging hook 23 pivoted on the pin 24 95 upon the side wall 6. The knife plunger 14 is provided with a right-angle portion known as the right arm designated 25 which carries a depending knife 26. The downward movement of the knife plunger is guided at the top of the knife plunger by the 100 guide bracket 27 at the bottom of the horizontal guide plate 28 which is fastened at 29 to the side wall 1 of the cabinet and rests primarily on the bottom 30 of the drawer compartment. 30 acts as a support for the 105 drawer.

The knife plunger is constantly being drawn downwardly by a helical spring or

knife retractor 31 which surrounds the lower end of the knife plunger and is carried by it beneath the bottom part 30. The spring is embraced at either end between a washer 6 32 carried by the knife plunger 14 and a washer 33 embraced between the upper end of the spring 31 and the bottom part 30.

The upper end of the plunger 14 and the knife arm 25 are adapted to be projected 10 through an aperture 34 through the top 4. This aperture is partially covered by a rectangular plate 35 having a rectangular aperture 36. It is through this aperture that the upper end of the knife plunger 14 and the knife arm 25 are projected. Beneath this frame 35 there is a glass inspection plate 36a. The autograph card 37 is carried beneath the glass inspection plate and is supported by the top 4 in a surrounding frame 15 38. In the passageway 34 on either wall thereof are mounted the plates 39 carrying the retaining or tearing hooks 40 which are directly beneath the card 37. This card is provided with an aperture 41 into which the 20 tearing knife or tearing pin 26 is inserted which prevents the card from being extracted after it has been once inserted down the incline guideway 42 beneath the plate 35 and the glass 36.

30 *Operation.*

Referring to Figures 6, 7, 8, where the parts used in the operation of the device can be more clearly seen:

35 Fig. 6 illustrates the parts in the position they would be left by a clerk after he had put the drawer in locked position. In Fig. 7 the parts are shown just before the clerk inserts his autographic card or 40 slip of paper on which he has written his name to autographically identify the card as having been inserted by him in position. Having placed the card in position he then shuts the drawer and the parts assume their 45 relationship shown in Fig. 6. If any unauthorized person attempts to pull the drawer out, in doing so the bracket support 8 will be moved away from the supporting pin 13 allowing the spring 31 to pull down 50 upon the plunger and tearing knife thus mutilating the card and indicating that some one unauthorized has tampered with the card and the drawer.

The vertical guiding plate 17 guides the 55 descent of the plunger until the pin 13 clears the bottom of 17, when the drawer can be completely opened. In the completely opened position as in Fig. 8 the pivoted portion 18 of the elevator passes over the pin 60 13 and drops down to a position in front of it so that it can elevate it when the drawer is closed as the pin will drop upon the surface 19 and thence upon the elevator until the pin drops in the notch 12 at which time 65 the card can be inserted if desired as in

approximately the position shown in Fig. 7, whereupon completely closing the drawer the pin 13 will drop down upon the bracket 8.

When the part 18 is held in its position 70 shown in dotted lines, Fig. 2, by the hook 23, this operation will not take place as 13 will not ride upon the top 18.

It will be understood that I do not desire to be confined to the detail embodiment illustrated and described but comprehend within my invention suitable modifications.

Having fully described my invention, what I claim as new and desire to secure by Letter Patent, is:—

1. In combination, a drawer, a cabinet, an autographic card holder in said cabinet, means to mutilate a card, means to elevate the mutilating means above the card position, and means to depress the mutilating means 85 to effect the mutilation, and means to retain the card relatively to the mutilating means to prevent extraction prior to mutilation, and means for preventing the operation of said mutilating means.

2. In combination, a drawer, a cabinet, an autographic card holder, means to mutilate the card, means to elevate the mutilating means above the card position, and means to depress the mutilating means to effect the 95 mutilation, means to retain the card relatively to the mutilating means to prevent extraction prior to mutilation, and cooperating means for assisting in the mutilation of the card.

3. In combination, a drawer, a cabinet, an autographic card holder, means to mutilate the card, means to elevate the mutilating means above the card position, and means to depress the mutilating means to effect the 105 mutilation, and means to render the elevating means inoperative.

4. In combination, a cabinet, a drawer working therein, an elevator carried thereby, a portion of which is stationary and a portion of which is movable, a reciprocating mutilating means carried by the cabinet, means on the mutilating means for engaging with the elevator for elevating the mutilating means when the drawer is being 110 closed and being adapted to pass over said means when the drawer is being opened, means to normally depress the mutilating means, and means to support a card beneath the mutilating means to be mutilated by it 115 when the drawer is opened.

5. In combination, a cabinet, a drawer working therein, an elevator carried thereby, a portion of which is stationary and a portion of which is movable, a reciprocating 125 mutilating means carried by the cabinet, means on the mutilating means for engaging with the elevator for elevating the mutilating means when the drawer is being closed and being adapted to pass over said means 130

- when the drawer is being opened, means to normally depress the mutilating means, and means to support a card beneath the mutilating means to be mutilated by it when the drawer is opened, and means on the forward end of the elevator for suspending temporarily the mutilating means to permit of the insertion of the card in position.
6. In combination, a cabinet, a drawer working therein, an elevator carried thereby, a portion of which is stationary and a portion of which is movable, a reciprocating mutilating means carried by the cabinet, means on the mutilating means for engaging with the elevator for elevating the mutilating means when the drawer is being closed and being adapted to pass over said means when the drawer is being opened, means to normally depress the mutilating means, and means to support a card beneath the mutilating means to be mutilated by it when the drawer is opened, and means on the forward end of the elevator for suspending temporarily the mutilating means to permit of the insertion of the card in position, and means carried by the drawer for supporting the mutilating means in engagement with the card but in a position not to destroy it until the drawer is partially opened.
7. In combination, a cabinet, a drawer working therein, an elevator carried thereby, a portion of which is stationary and a portion of which is movable, a reciprocating mutilating means carried by the cabinet, means on the mutilating means for engaging with the elevator for elevating the mutilating means when the drawer is being closed and being adapted to pass over said means when the drawer is being opened, means to normally depress the mutilating means, and means to support a card beneath the mutilating means to be mutilated by it when the drawer is opened, and means on the forward end of the elevator for suspending temporarily the mutilating means to permit of the insertion of the card in position, and means carried by the drawer for supporting the mutilating means in engagement with the card but in a position not to destroy it until the drawer is partially opened, and means on the drawer to prevent the disarrangement of the parts when the elevator moves out of engagement with the mutilating means.
8. In combination, a cabinet having an

opening in the top thereof, a drawer in said cabinet located beneath said opening, a frame encircling a portion of said opening, means adjacent the aperture in the top for the insertion of a card beneath the frame and the cabinet top, a knife arm and plunger adapted to pass through the apertures in said top, means on the knife for preventing the extraction of the card when in locked position, an elevator carried by the drawer adapted to engage with the plunger to elevate it, yielding means to normally depress the plunger, and means located beneath the card and cooperating with said knife as it descends to completely mutilate said card.

9. In combination, a cabinet having an aperture in the top thereof, a drawer in said cabinet beneath said opening, a reciprocating plunger arm carrying a knife adapted to pass through said aperture, yielding means to normally depress said plunger arm and knife, an elevator carried by said drawer having a portion thereof stationary and a portion movable, a knife plunger support adjacent one end of the elevator carried by the drawer, a temporary support on one end of the elevator, and vertical guide for the knife plunger carried by the drawer.

10. In combination, a cabinet having an aperture in the top thereof, a drawer in said cabinet located beneath said aperture, a reciprocating plunger arm carrying a knife adapted to pass through said aperture, yielding means to normally depress said plunger arm and knife, an elevator carried by said drawer having a portion thereof stationary and a portion movable, a knife plunger support adjacent one end of the elevator carried by the drawer, a temporary support on one end of the elevator, vertical guides for the knife plunger carried by the drawer, a guide near the top and a guide near the bottom for the knife plunger carried by the cabinet.

11. In combination, a cabinet having an aperture in the top thereof, a drawer working in said cabinet and located beneath said aperture, a frame encircling a portion of the aperture, means adjacent the aperture in the top for insertion of a card beneath the frame and the cabinet top, and a mutilating means adapted to be projected through the aperture in the frame.

In testimony whereof, I affix my signature.

JOHN M. GALE.
